TRAVELING CRANE MOTOR CONTROL

Kaikobad S. Kuka, Jamshedpur, Bihar, India

Application December 23, 1948, Serial No. 67,014

3 Claims. (Cl. 318—246)

1

The invention relates generally to systems of control and more particularly to the system of control for direct current motors employed in operating of the long travel mechanism of the electrically operated travelling cranes.

The object of the invention, generally stated, is to provide for controlling the overspeeding as also electromechanical braking of the long travel motion of a travelling crane.

A more specific object of the invention is to prevent overspeeding of a long travel bridge of a crane when the crane is running without any load on the hook, permitting at the same time, the maximum speed when the crane is handling its full load.

A further object of the invention is to provide the standard series type electro-mechanical brake, which drops only when the bridge stops or when the power fails.

For a better understanding of the invention, reference may be made to the following description taken in conjunction with the accompanying drawing, wherein:

The figure is a schematic illustration of a control system wherein the features pertaining to my invention are introduced.

In the drawing an electric motor of the direct current series type is shown provided with an armature A with a series field winding SF, which may be suitably coupled to the operating mechanism of a crane bridge. Since the constructions of the crane bridge long travel mechanism and the manner of installing the motors for operating them, as well as that of mounting of the electro-mechanical brakes are well known, it is not deemed necessary to illustrate these. Notation SB denotes the series type operating coil of the electro-mechanical brake, which is mounted on the motor shaft extension (not shown).

A master switch with a number of cam-operated contacts is provided to control the operation of the motor. The contact segment *a* of the master switch is disposed to engage the contact finger *a* which in turn is connected to the line conductor L1. The finger *a* is also connected over the auxiliary contacts Ma of the line contactor M to give the holding power to the coil M1 when the control switch is put on to energize the control panel. Contact segment *b* engages the finger *b* to provide the energizing circuit to the coil TF1 of the contactor TF. Contact segment *c* engages the finger *c* for completing the energizing holding circuit for the control when the master switch is moved from its "off" position. Contact segment *d* engages the finger

2

d for completing the energizing circuit for operating coils 1F1 and 2F1 of the directional contactors 1F and 2F, which when completed effect the closing of contactors 1F and 2F. Therefore, when the control switch is closed and the master switch is kept with its operating handle in the "off" position, the main line contactor M is energized and closes its main contacts at M and auxiliary contacts Ma over which the holding circuit for the operating coil M1 is obtained.

When the master switch is moved in the direction marked "forward" X to position 1, the contactors 1F and 2F are closed and the power circuit for the motor which may be traced from the line conductor L1, over the closed main switch, through the contactor 1F, the armature A, the contactor 2F, the series field winding SF, the electro-mechanical brake coil SB resistor R, main line contactor M over the main switch to line L2.

The motor is thus caused to operate in one direction called the forward direction and marked X. The resistor R is provided to prevent the excessive starting currents in the motor and also for making it possible to operate the motor at different speeds. In order to short-circuit the sections R1, R2, R3 and R4 of resistor R, the electro-magnetic contactor P, 1A, 2A and 3A are provided. P is called the plugging contactor and 1A, 2A and 3A are called the accelerating contactors, when the master switch is moved through different indicated "forward" positions 2, 3, 4 and 5, the contact fingers *c*, *d*, *f*, *g*, *h*, *i* and *j* engage the contact segments *c1*, *d1*, *f1*, *g1*, *h1*, *i1* and *j1* in the order named, completing the energizing circuits for the contactor coils 1F, 2F, P, 1A, 2A and 3A in sequence, which contactors in closing, short-circuit the respective resistor steps and accelerate the motor.

In order, however, to allow the motor to accelerate smoothly without heavy current kicks, the accelerating contactors 1A, 2A and 3A are controlled by the relay 1AR, 2AR and 3AR which are called accelerating magnetic time relays. The actuating coil 1ARI of the relay 1AR is connected across the resistor R1, that of 2ARI across the resistors R1 and R2 in series connection, and that of 3ARI across the resistors R1, R2 and R3 in series connection. These relays are actuated by the voltage drops across the resistor steps to which they are connected. As soon as the motor takes its starting current, the relays 1AR, 2AR and 3AR are actuated, pulling in their armatures. Each relay has a set of normally closed contacts which open out as soon as the relays are energized.

Another relay marked PFR is connected across the motor armature over the auxiliary contacts $1F_a$ of the contactor $1F$ and over control resistance r_3 to the point r_3 of the resistor step R_2 . This relay PFR is designed to be actuated by the combined voltage drops across the armature and the resistor R_1 and R_2 . When the relay coil PFR of the plugging relay for forward and reverse directions, is actuated, its normally open contacts PFR close and give the actuating power to the contactor coil P_1 over the finger g and segment g_1 of the master switch.

When the master switch is in position 2, contactor coil P_1 is energized over the contact PFR of the said plugging relay which pulls in as soon as the motor is connected to the line. When the contactor P closes, the resistance step R_1 is shorted. This short-circuits the coil of the relay $1AR$. This relay being a time delay relay, it takes time to open out. As soon as the relay $1AR$ drops out, its contacts $1AR$ close, giving circuit to the accelerating contactor coil $1A_1$, allowing the contactor $1A$ to close in its sequence. The contactor $1A$ in turn short-circuits the resistor R_2 and the coil $2AR$ of the its relay which then opens out and closes its contacts to allow $2A$ contactor to go in, which in turn de-energizes the coil $3AR$ of its relay which allows the contactor $3A$ to be pulled in. Thus when the master switch is moved fast to position 5 in "forward" direction, the motor is accelerated smoothly in a fixed time sequence, independent of the speed of moving the master switch handle.

When it is desired to move the crane in the opposite direction, i. e., in the reverse direction X_1 , the master switch is moved in direction indicated "reverse," when the control segments e_1 , f_2 , g_2 , h_2 , i_2 and j_2 engage the fingers e , f , g , h , i , and j in sequence. In the position 1 of "reverse" direction, the contactors $1R$ and $2R$ get energized which connects the armature A in the reversed polarity, allowing the motor to move in the opposite direction. The control of the contactors P , $1A$, $2A$ and $3A$ is however exactly the same as in the forward position of the master switch.

If, however, it is desired to bring the motion to a dead stop when the motor is moving in one direction, say forward, the master switch handle is brought suddenly to the "reverse" direction. The motor armature gets disconnected from its forward direction by dropping out of the contactors $1F$ and $2F$, and is at once connected to reverse direction by the energizing of the contactors $1R$ and $2R$. The motor is thus electrically connected to rotate in the opposite direction, whereas due to the momentum of the crane the armature is still kept rotating in the initial forward direction. The motor thus automatically generates a braking action which slows down the bridge motion. The process of stopping the motor by reversing its armature connections is technically known as electrical plugging. During the plugging period, the voltage across the relay coil PFR is almost zero. The relay thus drops out, opening its contacts, which opens the energizing circuit to the contactors P , $1A$, $2A$ and $3A$, allowing the whole resistance R to remain in the circuit to limit the current through the motor.

The above describes in general the operation of a standard reversing plugging magnetic controller as normally used on crane service.

When direct current series-wound motors are used on crane service, the ultimate speed de-

pend on the actual load on the motor. The characteristics of the series-wound motor is such that its speed increases as the load on the motor is reduced. Thus if a motor is selected on the basis of starting torque and the mechanism is geared on the basis of a certain definite speed on full load, it is clear that the ultimate speed increases as the load is reduced, and in case of a crane with no load on the hook, the ultimate speed becomes sometimes as high as 200% of the full load speed. When therefore the motion is to be arrested from that high speed, the shocks on the crane as well as the building are increased manifold because the shocks vary as the square of the speed. The adverse effects of these shocks on the buildings can therefore be reduced if it is possible to prevent the overspeeding of the motor at light loads.

To arrest the speed of the crane in an emergency when electrical power suddenly fails, a mechanical brake is absolutely necessary. To that end, it is possible to provide a mechanically operated foot brake, or an electro-mechanical brake, or an electro-hydraulic brake. The mechanically operated foot brakes were first tried and rejected as they depend on the operator and give a good deal of trouble due to long leverage. They were then discarded in favour of electro-mechanical brake. The series type electro-mechanical brake, though the simplest in operation, has not been generally adopted for long travel motion, because in actual service, it suddenly sets-in whenever the master switch handle is moved through the "off" position to change the direction of motion. This creates a sudden jerk on the crane, causing swinging of the load hanging on the hook creating difficulties in load spotting. It has therefore not been used in practice.

The shunt-type electro-mechanical brake is more common as it remains released as long as the power is available. The brake coil however has to be energized all the time and requires definite electrical interlocking with the main control so that the control is kept ineffective unless the brake is first energized. This creates a good deal of trouble in practice.

The present day general trend is to use hydraulic or electro-hydraulic brakes. These brakes have proved effective, but largely depend on the proper functioning of the mechanism free from air pockets, and require definitely increased and more intelligent and careful maintenance.

In my invention, a scheme of control is devised, which stabilizes the maximum light load speed of the motor, without reducing the set full load speed, and simultaneously allows the use of the simple and well tried out series-type electromechanical brake for emergency braking and holding of the motion.

The invention is fully described with reference to the attached drawing as follows:

(a) A circuit parallel to the motor armature A is added, controlled over normally open contacts of an electro-magnetic contactor denoted as TF and called in this art as teaser field contactor, in series with which a resistor R_5 is so connected that when the contactor TF is energized, the series field SF of the motor gets a direct circuit to the line L_1 in parallel with the armature.

(b) The value of the resistor R_5 can be selected so that the current passing independently through the series field SF over the parallel path, called the teaser field path, is limited to a fixed

value which gives a fixed limiting speed to the motor. It is proposed to set the resistance value R_5 to such an extent, that the maximum steady light hook speed of the motor is limited to 125% of its full load speed.

(c) The operating coil TF_1 of the contactor TF is connected to the finger b of the master switch. The contact segment b_1 of the master switch engages the finger b in the "off" position of the handle as well as in position 1 in both the "forward" and the "reverse" directions. In other positions from 2 to 5 the segment is disengaged from the finger. Simultaneously, the coil TF_1 is connected over normally open contacts $cemfa$ of the relay called counter-electro-motive-force relay, the coil $cemf_1$ of which is connected across the terminals of the armature A . To make the circuit of the coil TF_1 complete, the negative line is taken over the second set of contacts $cemfb$ of the relay, in series with the normally open auxiliary contacts TFa of the TF contactor itself; the negative terminal of the coil TF_1 is also taken over the normally open contacts $3ARa$ of the accelerating time relay $3AR$.

(d) The relay with coil $cemf_1$ which is connected across the armature terminals is set to pull its plunger in, closing its two sets of contacts $cemfa$ and $cemfb$, when the motor armature voltage reaches a fixed set value.

(e) Operation of the control system: To move the load from one position to another, the operator moves the master switch handle to position 5 in "forward" direction. The motor starts speeding up in sequence as the contactors $1F$, $2F$, P , $1A$ and $2A$ are energized one after the other. When the contactor $2A$ is pulled in, the relay coil $3AR_1$ is shorted and the relay begins to time out. With the closing of the $2A$ contacts, the resistors R_1 , R_2 and R_3 are all shorted, and the motor has only the resistor R_4 in the line. As soon as the resistor step R_3 gets shorted, the motor armature begins to accelerate faster, the rate of acceleration depending on the load on the crane hook. The rate of acceleration depends on the rate of change of armature back-electro-motive force. If the relay with coil $cemf_1$ pulls in earlier than the timing of the relay with coil $3AR_1$, the coil TF_1 gets energized over the contacts $cemfa$ and the contacts $3ARa$ both of which are closed at the same time. The contactor TF is therefore pulled in and the teaser field circuit is completed. The adjustments of the relay with coil $cemf$ and the relay with coil $3AR_1$ are so set that with one-third full load on the hook, relay with coil $3AR_1$ times out before relay with coil $cemf_1$ relay can pull in. Therefore, for all loads less than one-third full load, the teaser field circuit is completed, whereas for loads one-third and above, the control works as a normal series motor control. If the crane driver wants that the crane bridge should coast a short distance, it brings the master switch in the "off" position, when the contactors $1F$ and $2F$ have dropped down, disconnecting the motor armature from the power line. However, the coil TF_1 of the contactor TF remains energized over the master switch finger b which engages with the segment b_1 , which keeps the teaser field circuit energized. The series field of the motor remains energized along with the series brake coil, thus allowing the brake to remain lifted and the crane to coast. Referring to the drawing, it will be observed that on the first point of the master switch, the coil TF_1 gets connected to the positive power line over the master switch finger b . The connection is

traced from the positive pole L_1 of the control switch, over the fuse to the finger a of the master switch, then over the inter-connecting wire to the contacts Ma of the main contactor M . As 5 the contactor M is energized, Ma contacts are closed, which gives the connection to the finger c of the master switch. As the finger c makes a constant contact with its segment c_1 , the continuity of the circuit is maintained over the interconnecting bar between segments c_1 and b_1 10 to the finger b of the master switch because in position 1 of the master switch, segment b_1 contacts finger b . Finger b is connected to one of the terminals of the coil TF_1 . Thus in the position 1 of the master switch, either in forward or reverse direction, the coil TF_1 always gets connected to the positive line. The other terminal of the coil TF_1 is connected to the contacts $3ARa$ 15 of the relay $3AR$, the connecting wire being taken over one common terminal of the contacts $cemfb$ of the $cemf$ relay. If, therefore, the contacts $3ARa$ also remain closed, the coil TF_1 will be energized in the position 1 of the master switch, as it will be connected also to the negative power line over the closed contacts $3ARa$. The relay $3AR$ is energized by the voltage drop across the resistances $(R_1+R_2+R_3)$ being connected to points r_1 and r_4 of resistance R . With full load on the crane, when the master switch is brought 20 from position 5 to position 4, 3, 2, and 1 in sequence, the motor resistances are re-introduced into the motor circuit by dropping out of contactors $2A$, $1A$ and P . The voltage drop due to the current through resistance R is such that the relay $3AR$ will pick up and close its contacts $3ARa$ before the master switch comes to position 1. The coil TF_1 is thus energized as soon as the master switch is on position 1. Once the coil TF_1 is energized and contacts TF close, the relay $3AR$ is kept energized, as the current will 25 now branch off over the armature parallel circuit over the contacts TF , so that the voltage for the relay $3AR$ is maintained to keep its contacts $3ARa$ closed. When the master switch is brought to "off" position, the coil TF_1 , once energized on position 1, remains still connected to the power line as the circuit continuity is maintained even in the "off" position of the master switch. The electro-mechanical brake thus gets its holding power over the circuit given by the closing of the contacts TF . Therefore, whatever the load on the crane hook, the contactor TF gets energized as soon as the master switch is brought to position 1, and remains so even in the "off" position of the master switch. The brake thus 30 remains lifted and permits coasting of the bridge under all conditions. If the crane driver wants to stop the crane by plugging, he reverses the master switch handle, which applies the plugging operation as already explained above. If the crane driver wants to plug the crane from the position 3 of the master switch, in that case too, as soon as the master switch passes over position 1 the TF contactor pulls in, because the 35 relay with coil $3AR_1$ remains energized completing the energizing circuit of the coil TF_1 . The series brake thus remains energized during the changeover to plugging operating. The controller therefore works as if the series brake is not provided. Only when the bridge is at standstill or when the power fails, does the brake drop down to hold the motion. The control system thus prevents overspeeding of the crane bridge when running with light loads and permits the 40 use of a simple series type electromechanical

brake to arrest the motion in case of an emergency, or to keep the brakes applied when the crane is at a standstill.

Having now particularly described and ascertained the nature of my invention and the manner in which the same is to be performed, I declare that what I claim is:

1. An electro-magnetic controller especially for a long travel mechanism of an electric travelling crane employing an electric circuit combining a direct current series wound motor, a source of energy and a manually operable master switch for starting, plugging and reversing the motor, having voltage responsive means, an electro-magnetic relay responsive to voltage across the motor armature during acceleration, and time-delay responsive means, an electro-magnetic time-delay relay set for a fixed time interval, and motor speed control means, a current limiting resistor controlled by an electro-magnetic contactor and connected in parallel circuit connection with the armature winding, herein called the teaser field circuit, the said voltage responsive means and the said fixed time-delay operating means in combination controlling the said motor speed control means, strengthening the motor field by diverting a fixed value of current through the motor field winding holding speed of the motor to a fixed maximum value, the said speed control means being connected in the circuit only when the motor speed exceeds a fixed value within a fixed time interval.

2. An electro-magnetic controller especially for a long travel mechanism of an electric travelling crane employing an electric circuit combining a direct current series wound motor, a source of energy and a manually operable master switch for starting, plugging and reversing the motor, having voltage responsive means, an electro-magnetic relay responsive to voltage across the motor armature, and time-delay responsive means, an electro-magnetic time-delay relay set for a fixed time interval, and motor speed control means, a current limit resistor controlled by an electro-magnetic contactor connected in parallel circuit connection with the motor armature winding, herein called the teaser field circuit, the said motor speed control means being controlled by the said voltage responsive means, responsive to the electro-motive force across the motor armature and the said time-delay means comprising the said electro-magnetic time-delay relay responsive to the voltage drop across a current limit resistor in the motor field circuit, the said voltage responsive means in combination with the said time-delay operating means controlling the said speed control means, connecting the said teaser field circuit in parallel circuit connection with the motor armature, diverting a fixed value of current

through the motor field winding, so strengthening the motor field holding the motor speed to a fixed maximum value.

3. An electro-magnetic controller especially for a long travel mechanism of an electric travelling crane employing an electric circuit combining a direct current series wound motor, a source of energy and a manually operable master switch for starting, plugging and reversing the motor, having voltage responsive means, an electro-magnetic relay responsive to voltage across the motor armature, and time-delay responsive means, an electro-magnetic time-delay relay set for a fixed interval, and motor speed control means, a current limit resistor controlled by an electro-magnetic contactor connected in parallel circuit connection with the motor armature winding, herein called the teaser field circuit, and an electro-mechanical braking means, an electro-mechanical brake mounted on the motor shaft, its energising coil being connected in series connection with the motor armature winding and the motor field winding, the said motor speed control means being controlled by the said voltage responsive means responsive to the electro-motive force across the motor armature and the said time-delay means comprising the said electro-magnetic time-delay relay responsive to the voltage drop across a current limit resistor in the motor field circuit, the said voltage responsive means in combination with the said time-delay operating means, controlling the said speed control means, connecting the said teaser field circuit in parallel connection with the motor armature, diverting current through the motor field winding and through the energizing coil of the said electro-mechanical braking means in series connection with the motor field winding, the current through the operating coil of the electro-mechanical braking means, maintaining the energizing power and restraining the application of the electro-mechanical brake despite the reversible movements of the said manually operable master switch required to manipulate the direction of motion of the long travel mechanism of the crane.
